H. A. DOUGLAS.
CONTACT CARRIER.
APPLICATION FILED FEB. 4, 1918.

1,432,844.

Patented Oct. 24, 1922.

Inventor:
Harry A. Douglas.
By G. A. Clegg Atty.

UNITED STATES PATENT OFFICE.

HARRY A. DOUGLAS, OF BRONSON, MICHIGAN.

CONTACT CARRIER.

Application filed February 4, 1918. Serial No. 215,330.

To all whom it may concern:

Be it known that I, HARRY A. DOUGLAS, citizen of the United States, residing at Bronson, in the county of Branch and State 5 of Michigan, have invented a certain new and useful Improvement in Contact Carriers, of which the following is a full, clear, concise, and exact description.

My invention relates to contact carriers, 10 one feature of the invention residing particularly in contact carriers that are in the form of plugs. It is the object of this feature of my invention to provide a given plug for the reception of a terminal conductor 15 or conductors passed into the plug either from end to end of the plug or through a side of the plug and thence toward one end of the plug. This feature of my invention may be practiced in conjunction with a so-called single pole plug or a so-called double 20 pole plug.

In carrying out this feature of the invention I provide a plug with one bore, if the plug is a single pole plug or two bores if 25 the plug is a double pole plug, such bore or bores extending longitudinally through the plug. There is also provided one or two bores, as the case may be, which communicate with the aforesaid bore or bores and 30 extend laterally into the plug. The longitudinally disposed bore or bores are thus always in service in whole or in part whether the conductor or conductors are passed into the plug longitudinally or laterally thereof, 35 the lateral bores not being used, as the invention is preferably practiced when the conductors extend from end to end of the plug.

The plug is desirably divided lengthwise 40 into sections, a half of each bore being formed in each section of the plug. Where the plug is formed in sections it is desirably provided with a sheath for maintaining the sections in assembly.

45 The invention has for another of its objects the provision of improved means for holding a plug or other contact carrier, such as the plug hitherto described, in assembly with a shell of a circuit extending device. 50 In practicing this feature of my invention I employ a spring secured to and extending laterally of the shell and located to engage bayonet pins upon a plug or other carrier and hold them in their seats that are formed 55 in the bayonet slots in the shell. This spring

is preferably rigidly anchored to the shell at the intermediate portion of the spring and the spring itself extends transversely of the shell to have its ends engageable with the bayonet pins. 60

I will explain my invention more fully by reference to the accompanying drawing showing the preferred embodiment thereof and in which Fig. 1 is a view, in longitudinal section, illustrating a connector having 65 a shell and plug equipped in accordance with my invention, one of the two arrangements of conductors being shown in conjunction with the plug, a lamp being shown in elevation within the shell; Fig. 2 is a 70 view on line 2-2 of Fig. 1; Fig. 3 shows another disposition of conductors within the plug of the connector; Fig. 4 is a view in elevation of the structure as it appears in Fig. 3; Fig. 5 is a view in plan of the 75 rear part of the shell appearing in Fig. 4; Fig. 5^a is a view of the shell as it appears in Fig. 5 minus the retaining spring; Fig. 6 is a view in perspective showing the two parts of the core of the plug in separated 80 relation; and Fig. 7 shows in perspective the sheath that I prefer to employ for the plug when it is used as illustrated in Fig. 1.

Like parts are indicated by similar characters of reference throughout the different 85 figures.

The shell 1 of the connector is preferably metallic. Its front end is provided with bayonet slots 2 adapted to receive the bayonet pins 3 that project laterally from the 90 base 4 of the incandescent lamp 5. The filament 6 of the lamp is connected with the contacts 7 and 8 that are provided upon the base of the lamp. Both of these contacts are shown as being upon the inner end face of 95 the lamp base inasmuch as the connector illustrated is a so-called two pole connector, but to which type of connector the invention is not to be limited. A contact carrier 9, of insulating material, is fixedly located in 100 the mid portion of the shell. Metallic spring barrels 10 and 11 are secured to and pass through the contact carrier 9. Coiled springs 12 and 13 are located within the spring barrels. These coiled springs press 105 the contact plungers 14 and 15 forwardly to have them respectively engage the contacts 7 and 8 upon the lamp base. These same springs press the contact plungers 16 and 17 rearwardly to engage them with con- 110

tacts 18 and 19 that are suitably connected with the terminals of a source of current through the intermediation of flexible conductors 20 and 21.

5 The contacts 18 and 19, the conductors 20 and 21 leading to these contacts and the coverings or serving for these conductors are disposed within and are carried by a contact carrying plug of insulating material, which contact carrying plug is preferably divided longitudinally into sections by being symmetrically formed into halves 22-23 as illustrated in Fig. 6. Two cylindrical bores 24, 25 extend longitudinally 10 through the contact carrying plug 22-23, the half of each bore being formed in each half of said contact carrying plug. Transversely extended bores 26, 27 merge with the bores 24, 25, the bores 26, 27 being curved 15 forwardly to merge gradually with the other bores. A half of each of the bores 26, 27 is formed in each half of the contact carrying plug 22-23. When the conductors 20, 21 extend into the plug 22-23 laterally of 20 such plug the sheath 28, clearly illustrated in Fig. 7, is employed, the bore of this sheath being equal in diameter to the diameter of the plug whereby the two halves of the plug are prevented from slipping 25 transversely of the sheath. The rear ends of the plug halves 22, 23 abut against the rear end wall 29 of the sheath 28. The forward end of the sheath is turned inwardly, as indicated at 30 in Fig. 1, to engage the 30 front ends of the plug halves 22, 23. The two halves of the plug are thus prevented from slipping endwise with respect to each other. A ferrule 31 encloses the conductors 20 and 21 and a tube 32 through which these 35 conductors are led. This ferrule has a head or flange 33 that is located within the interior of the sheath 28, said ferrule projecting into this sheath through the slot 34 that is formed longitudinally of the sheath 28 40 to permit the ferrule to be slipped into the sheath from the front end thereof.

In the arrangement illustrated in Fig. 1 the conductors 20 and 21 first pass through the bores 26, 27 before passing into the 50 bores 24, 25. In the arrangement illustrated in Figs. 3 and 4, the conductors project through the rear end of the contact carrying plug 22-23 extending throughout the entire length of the bores 24, 25 and passing 55 through no part of the bores 26, 27. In this arrangement the ferrule 31 is omitted and the sheath 28¹ is minus the longitudinal slot 34 but has its rear end open as indicated at 35 in order that the conductors may pass 60 from the plug. To maintain the conductors 20, 21 and their terminal contacts 18 and 19 in assembly with the contact carrying plug 22-23, I provide said contacts with flanges 35, 36 that are received within the annular 65 enlargements 37, 38 of the bores 24, 25.

The sheath of the plug 22-23, whether of the form illustrated in Fig. 1 or of the form illustrated in Fig. 3, is provided with bayonet pin extensions 39 receivable within bayonet slots 40 provided in the rear end 70 of the shell 1. Instead of relying upon the contacts 16 and 17 to maintain the bayonet pins 39 in their seats within the bayonet slots or channels 40 I provide a strip or wire retaining external spring 41 extending laterally of the shell and disposed in the zone of the bayonet slots or channels 40 and which retaining spring has an arrangement that is well illustrated in Figs. 2, 3 and 5. This spring extends laterally and conforms generally to the curvature of the shell and is depressed at its intermediate portion 41¹ to contact with the sheath 28 or 28¹ of the plug, this depressed portion being received in the transverse slot or opening 42 and being substantially co-extensive with this slot to have abutting engagement at the ends of the slot where the spring rises to have its sections 41² engage the exterior of the shell 1. The ends of the retaining spring are 80 depressed to enter the bayonet slots 40 and engage the sheath 28 or 28¹, these spring ends extending across the entrance branches of the bayonet slots 40 to be engaged by the bayonet pins or projections 39. When the 85 plug 22-23 is inserted the bayonet pins or projections 39 engage the spring 41 and flex it longitudinally of the shell from its normal plane, this plane being resumed by the spring when the bayonet pins are in 90 their seats owing to the resilience of the spring and the substantially fixed anchorage of the spring at its mid portion to the shell, the ends of the spring 41 serving to hold 95 these bayonet pins in their seats. Any 100 preferred means may be employed for holding the spring 41 in assembly with the shell 1. In the preferred embodiment of the invention two ears 43 are struck up from the shell where the mid portion 41¹ of the 105 spring is received and are lapped over this intermediate portion of the spring to hold the spring in the assembly illustrated clearly 110 in Fig. 2. These ears 43 serve to co-operate with the contiguous portions of the shell 115 and also with the underlying sheath normally to hold the spring in its plane, the engagement of the spring and shell being sufficiently firm to establish a substantially 120 fixed relation between the mid section 41¹ of the spring with the shell so that the spring is merely permitted to yield, due to its own resilience, when the plug 22-23 is 125 being inserted within or removed from the shell. The ends of the spring are depressed into the bayonet slots to engage the sheath of the plug and thereby have full effective engagement with the bayonet pins. While the spring 41 is shown for the purpose of 130 holding the plug in assembly with the shell

it is obvious that it is not limited to the nature of the contact carrier that it serves to hold in position.

The plug structure herein disclosed and parts in association therewith form the subject matter of a division of this application Serial No. 258,065, filed October 14, 1918.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. The combination with a shell having bayonet channels therein; of a contact carrier provided with bayonet projections receivable in said bayonet channels; and a spring extending laterally of and substantially fixedly secured at an intermediate portion to the shell, the ends of said spring being located to engage said bayonet projections and hold them in their seats, the intermediate and end portions of the spring extending into engagement with the contact carrier through openings provided in the shell.
2. The combination with a shell having bayonet channels therein; of a contact carrier provided with bayonet projections receivable in said bayonet channels; and a spring extending laterally of and substantially fixedly secured at an intermediate portion to the shell, the ends of said spring being located to engage said bayonet pro-

jections and hold them in their seats, the end portions of the spring extending into engagement with the contact carrier through 40 openings provided in the shell to engage the bayonet projections that extend into these openings and elsewhere engaging the exterior of the shell.

3. The combination with a shell having 45 bayonet channels therein; of a contact carrier provided with bayonet projections receivable in said bayonet channels; and a spring extending laterally of and substantially fixedly secured at an intermediate portion to the shell, the ends of said spring being located to engage said bayonet projections and hold them in their seats, the 50 intermediate and end portions of the spring extending into openings provided in the 55 shell.

4. The combination with a shell having bayonet channels therein; of a contact carrier provided with bayonet projections receivable in said bayonet channels; and a 60 spring extending laterally of and substantially fixedly secured at an intermediate portion to the shell, the ends of said spring being located to engage said bayonet projections and hold them in their seats, the 65 end portions of the spring extending into openings provided in the shell to engage the bayonet projections that extend into these openings.

In witness whereof, I hereunto subscribe 70 my name this thirtieth day of January, A. D., 1918.

HARRY A. DOUGLAS.
